Primary Examiner — Celia Murphy*Assistant Examiner* — John Windmuller(74) *Attorney, Agent, or Firm* — Kilpatrick Townsend & Stockton LLP(57) **CLAIM**

The ornamental design for a clip, as shown and described.

DESCRIPTION

FIG. 1 is a front perspective view of a clip showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is right side elevational view thereof;

FIG. 8 is left side elevational view thereof;

FIG. 9 is a front perspective view thereof showing the location of the cross section of FIG. 10; and,

FIG. 10 is a sectional view thereof taken on line 10—10 in FIG. 9.

The broken line showings form no part of the claimed design.
